UNITED STATES PATENT OFFICE.

ROBERT M. HOOD, OF FORT MILL, SOUTH CAROLINA, ASSIGNOR OF ONE-THIRD TO
AUSTIN R. McELHANEY AND ONE-THIRD TO JOHN J. BAILES, BOTH OF FORT
MILL, SOUTH CAROLINA.

FENDER.

1,176,060.

Specification of Letters Patent. Patented Mar. 21, 1916.

Application filed January 25, 1913. Serial No. 744,261.

To all whom it may concern:

Be it known that I, ROBERT M. Hood, a citizen of the United States, residing at Fort Mill, in the county of York and State 5 of South Carolina, have invented a new and useful Fender, of which the following is a specification.

The device forming the subject matter of this application is a fender adapted to be 10 connected with the truck of a railway car or with any other portion of rolling stock of any description, the function of the device being to thrust outwardly, beyond the wheel, any object which may be located above the 15 rail. Specifically, the device is of peculiar utility for preventing the foot of a person from being caught between the wheel and the track.

The invention aims to provide a fender of 20 this type which may be attached readily to railway rolling stock of standard constructions, without altering the form of the rolling stock and without employing connecting elements other than those commonly met 25 with.

Another object of the invention is to provide a fender so constructed that its resiliency will render it peculiarly efficient.

It is within the scope of the invention to 30 improve generally and to increase the utility of, devices of that type to which the present invention appertains.

With the foregoing and other objects in view which will appear as the description 35 proceeds, the invention resides in the combination and arrangement of parts and in the details of construction hereinafter described and claimed, it being understood that changes in the precise embodiment of 40 invention herein disclosed can be made within the scope of what is claimed without departing from the spirit of the invention.

In the drawing:—Figure 1 shows, in side elevation, a truck equipped with a fender 45 constructed in accordance with the present invention; Fig. 2 is an end elevation showing the device applied; and Fig. 3 is a perspective of the fender.

In the drawing, although the device may 50 be variously mounted, the bearing boxes of a truck are shown and indicated by the numeral 1, the bearing boxes, as usual, supporting the axles 2 carrying the wheels 3. A brace 4 is shown, the same, in the present

instance, although not necessarily, being of 55 diamond shape. The brace 4 rests upon a tie 5. The ends 6 of the brace 4 rest upon the upper surfaces of the bearing boxes 1 and the ends 7 of the tie 5 bear against the under faces of the boxes. Securing elements 60 which may be bolt and nut structures 8 pass through the ends 6 of the brace 4 and through the ends 7 of the tie 5 to hold these elements, which constitutes a frame, upon the bearing boxes 1. 65

The fender herein disclosed is fashioned preferably from a single plate of resilient metal and is approximately of a common width from one end to the other. The fender comprises a body 9 which, adjacent 70 one end is curved as shown at 10 to form a laterally extended deflecting lip 11. An ear 12 is formed integrally with the body 9 of the fender and is located at the upper edge of the body 9, the ear 12 having openings 14 through which the securing elements 8 pass, to bind the ear 12 against the lower face of the end 7 of the tie 5, as clearly shown in Fig. 1. Ordinarily and preferably 75 one of the fenders hereinbefore set forth is 80 employed in connection with each wheel of the truck although, obviously, upon a six wheeled truck, but four fenders need be used. 85

Special attention is directed to the fact 85 that it is entirely unnecessary to change the structure of the truck in any degree. The securing elements 8, constituting a part of the truck, may be employed for holding the fender in place, and the fender itself is the 90 only element which need be supplied.

Owing to the fact that the relatively long, resilient body 9 is interposed between the ear 12 and the deflecting lip 11, the fender will impose no severe shock upon the person or object which is encountered. However, the fender is not sufficiently resilient to nullify its effect as a mean for forcing the object laterally with respect to the rail. The body 9 adjacent the lip 11 is plane and 100 unencumbered upon its upper and lower edges, and is of a common width, so that the resiliency of the fender will not be impaired. Not only may the fender bend resiliently parallel with the ear 12, but, because the ear 12 is secured to the upper edge of the fender, the body 9 may yield in a direction at right angles to the plane of the 105

ear 12. Thus, the lower edge of the fender will act yieldingly in forcing objects off the rail.

Having thus described the invention, what is claimed is:—

The combination with a car truck, of separate fenders connected to the respective ends of the truck, each fender including a flat upstanding body extending along the outside of and parallel with one of the wheels of the truck and having one end portion curved inwardly across the path of movement of the wheel and forming a deflecting lip, said lip being disposed diagonally across the path of the wheel and throughout the length of the lip whereby an object contacting with any portion of the lip will be deflected outwardly away from

the truck, all portions of the body and lip standing vertically thereby to avoid a tripping action, the upper and lower edges of the lip being horizontal and parallel throughout the extent of the lip, there being an outwardly extending ear upon the upper edge portion of the body adjacent that end of the body remote from the lip, said ear being secured to the bottom of a portion of the truck, the bodies of the two fenders at the sides of the truck being spaced apart.

In testimony that I claim the foregoing as my own, I have hereto affix my signature in the presence of two witnesses.

ROBERT M. HOOD.
